US0D1020673S

(12) **United States Design Patent** (10) Patent No.: **US D1,020,673 S**
(45) Date of Patent: ** Apr. 2, 2024

(54) **TELEVISION RECEIVER**

(71) Applicant: **LG ELECTRONICS INC.**, Seoul (KR)

(72) Inventors: **Sharim Choe**, Seoul (KR); **Daihyung Ryu**, Seoul (KR); **Yoonyoung Cho**, Seoul (KR)

(73) Assignee: **LG ELECTRONICS INC.**, Seoul (KR)

(**) Term: **15 Years**

(21) Appl. No.: **35/515,495**

(22) Filed: **Apr. 26, 2022**

(80) **Hague Agreement Data**

Int. Filing Date: **Apr. 26, 2022**

Int. Reg. No.: **DM/220557**

Int. Reg. Date: **Apr. 26, 2022**

Int. Reg. Pub. Date: **Oct. 28, 2022**

(30) **Foreign Application Priority Data**

Nov. 23, 2021 (KR) 30-2021-0056066

(51) **LOC (14) Cl.** **14-03**

(52) **U.S. Cl.**

USPC **D14/126**
